DESIGN FOR A BOTTLE

Lee C. Ward, Los Angeles, Calif., assignor to Tru-Ade Inc., Los Angeles, Calif., a corporation of California

Application November 23, 1938, Serial No. 81,308

Term of patent 14 years

To all whom it may concern:

Be it known that I, Lee C. Ward, a citizen of the United States, residing at Los Angeles, county of Los Angeles, State of California, have invented a new, original, and ornamental Design for a Bottle, of which the following is a specification, reference being had to the accompanying drawing forming part thereof. Figure 1 is a side elevational view of the bottle showing my new design; and Figure 2 is a sectional view thereof, in line 2—2 of Figure 1.

I claim:

The ornamental design for a bottle, as shown.

LEE C. WARD.
